UNITED STATES PATENT OFFICE.

JOHN FLINDALL, OF CHICAGO, ILLINOIS.

TIME-LOCK.

No. 884,809.

Specification of Letters Patent. Patented April 14, 1908.

Application filed May 31, 1907. Serial No. 376,535.

To all whom it may concern:

Be it known that I, JOHN FLINDALL, a citizen of the United States, residing at Chicago, in the county of Cook and State of Illinois, 5 have invented certain new and useful Improvements in Time-Locks; and I do hereby declare the following to be a full, clear, and exact description of the invention, such as will enable others skilled in the art to which 10 it appertains to make and use the same.

This invention relates to time locks and especially to that class of locks controlled by clock-work mechanism, and has for an object to provide a lock of the class embodying 15 improved features of reliability, simplicity and economy.

A further object of the invention is to provide in a lock a clock-work mechanism of substantially the usual and ordinary form together with means for operating the tumblers and with improved means for rotating the tumbler operating mechanism without actuating the clock-work.

With these and other objects in view, the 25 invention comprises certain novel constructions, combinations and arrangements of parts, as will be hereinafter fully described and claimed.

In the drawings:—Figure 1 is a view in side 30 elevation of a safe door with a part of the inner wall removed showing the operative parts. Fig. 2 is a sectional view longitudinally of the tumbler axis showing the tumblers and tumbler-actuating means in section.

Like characters of reference designate corresponding parts throughout the several views.

The improved lock is adapted for use in 40 association with any ordinary or approved safe or vault door conventionally shown as the outer wall or casing numbered 10, and in Fig. 1 with the inner wall 11 broken away. Within the casing of the door is mounted a 45 clock shown conventionally at 12 with a face, as 13, visible without the inner casing of the door. Substantially parallel with the several shafts of the clock is also mounted a shaft 14 extending through the outer wall or casing of 50 the door and provided with substantially the usual and ordinary tumbler knob 15 rigidly connected with the said shaft 14. To the inside of the outer shell or casing 10 a sleeve 16 is secured and within said sleeve the shaft 14 rotates, and a tumbler 17 is mounted rigidly upon the inner end of the shaft 14 and

abutting the inner end of the sleeve 16. Upon the sleeve 14 are also mounted to rotate the usual and ordinary tumblers 18 and 19 operated one from the other by the employment of the usual lugs 20 so that as the tumbler 17 is rotated from the knob 15, the lug thereof engages the lug upon the tumbler 18 to rotate such tumbler which in turn engages the lug of the tumbler 19 to rotate such 65 tumbler. Mounted also to rotate upon the sleeve 16 is a tumbler 21 rigidly connected and concentric with a gear wheel 22 which said gear interengages with a pinion 23 mounted upon a shaft 24. Upon the shaft 70 24 is also mounted a gear 25 intergeared with a pinion 26 upon a shaft 27. Upon the shaft 27 are also mounted a ratchet wheel 28 and a pinion 29 having a spring pressed pawl 30 positioned to engage with and to operate the 75 ratchet wheel.

Adjacent the shaft 27 is journaled a shaft 31 carrying a pinion 32 intergeared with the pinion 29, and a gear 33 intergeared with a gear 34 forming one of a train of gears of the 80 clock-work mechanism. It will thus be seen that as the clock-work mechanism rotates under the impetus of the clock motor the train of gears rotates and rotates the wheel 22 and its associate tumbler 21. It will also 85 be seen that the gear 22 may be rotated independently of the train by reason of the ratchet wheel 28, ratchet wheel 29 and pawl 30. To rotate such wheel 22 independently a pinion 36 is provided having a crank arm 90 or lever 37 extending through the inner wall of the door and in position for engagement upon the inner side of the door. Within the door structure are also mounted the bolts 38 and 39 connected by the cross head 40 and 95 operated by means of a lever 41 mounted upon the shaft 42 to which is connected upon the outer surface of the door the usual and ordinary tumbler operating handle or lever. The lever 41 engages a stud 43 carried upon the arm 44 rigid or integral with the cross head 40. Pivoted within the door structure is also a lever 45 positioned and proportioned to engage the inner end of the arm 44 and to hold the bolts 38 and 39 in extended position as shown in Fig. 1 when the end of the lever 45 abuts the end of the arm 44. 100

The lever 45 is provided with a nose 46 proportioned to drop within the registering recesses 47 formed in the several tumblers 17, 18, 19 and 21. It will thus be seen that 110 when the clock-work mechanism rotates the

wheel 22 to the proper position the recess 47 in the tumbler 21 is positioned to permit the nose 46 to drop into such recess. The lever, however, cannot drop until all of the tumblers 17, 18 and 19 have their recesses 47 in alinement with the recess of the tumbler 21. The positioning of the recesses of the said tumblers 17, 18 and 19 is accomplished manually by rotation of the knob 15 to bring such recesses into alinement with the recess of the tumbler 21. It will thus be apparent that the tumblers 17, 18 and 19 cannot be so manipulated that the lever will fall unless the tumbler 21 is also in position and moved thereby by the action of the clock-work nor can the lever fall when the tumbler 21 is in position unless all of the other tumblers are also in alinement.

About the wheel 22 is formed a scale 48, and a pointer 49 is disposed at any approved point to indicate the necessary and desirable characters upon the scale so that by manipulating the lever 37 the wheel 22 may be rotated until the pointer 49 indicates the necessary marking upon the scale which will indicate the time at which the clock-work will move the tumbler 21 into proper position.

What I claim is:—

30 1. In a lock, a plurality of tumblers independently operatable, means to operate some of said tumblers manually, means to operate another of said tumblers mechanically, and means to move the mechanically operated tumbler relative to the operating means.

2. In a lock, a plurality of tumblers, some of said tumblers being operatable manually, a clock, means connecting the clock with another of said tumblers, and means to move the tumbler operated by said clock independently of the clock.

3. In a lock, a sliding bolt, an extension carried by said bolt, a lever adapted to abut the extension and hold the bolt extended, a

plurality of tumblers provided with recesses 45 proportioned to permit the lever to drop out of engagement with the extension, means to operate some of said tumblers manually, and means to operate one of said tumblers mechanically.

4. In a lock, a sliding bolt, an extension carried by said bolt, a lever adapted to abut the extension and hold the bolt in extended position, a nose formed upon the lever, a plurality of independently rotatable tumblers 55 provided with recesses proportioned to receive the nose, means to rotate some of said tumblers manually, and means to rotate one of said tumblers mechanically.

5. In a lock, a sliding bolt, an extension carried by said bolt, a pivoted lever proportioned to abut the extension and hold the bolt in extended position, a nose formed upon the lever, a plurality of independently rotatable tumblers each provided with a recess 65 proportioned to receive the nose, means to rotate some of said tumblers manually, a clock, means connected with the clock for rotating one of said tumblers therefrom, and means to rotate said tumbler independently 70 of the clock.

6. In a lock, a sliding bolt, a pivoted lever adapted to hold the bolt in extended position, a nose formed upon the lever, a plurality of tumblers provided with recesses 75 proportioned to receive the nose, means to rotate some of said tumblers manually, a clock, a train of gears connecting the clock with and to rotate one of said tumblers, and a ratchet interposed in the train of gears 80 whereby the latter tumbler may be rotated independently of the clock.

In testimony whereof I affix my signature in presence of two witnesses.

JOHN FLINDALL.
